UNITED STATES PATENT OFFICE.

EVALD J. ENGMAN, OF SYRACUSE, NEW YORK, ASSIGNOR TO THE WILL & BAUMER CO., OF SYRACUSE, NEW YORK, A CORPORATION OF NEW YORK.

PISTON AND PLUNGER CONSTRUCTION.

1,258,549.

Specification of Letters Patent.

Patented Mar. 5, 1918.

Application filed March 8, 1917. Serial No. 153,255.

To all whom it may concern:

Be it known that I, EVALD J. ENGMAN, a citizen of the United States, and a resident of Syracuse, in the county of Onondaga 5 and State of New York, have invented a certain new and useful Piston and Plunger Construction, of which the following is a specification.

This invention has for its object a piston 10 construction particularly applicable for candle molding machines or in other situations in which a grease or liquid tight piston is desirable, which construction is especially simple and economical; and the invention 15 consists in the novel features hereinafter set forth and claimed.

In describing this invention, reference is had to the accompanying drawings in which like characters designate corresponding 20 parts in all the views.

Figure 1 is a sectional view of a piston embodying my invention and used in connection with candle molding machines, the contiguous part of a candle molding machine being also shown.

Fig. 2 is a face view of the piston, partly broken away.

Fig. 3 is an elevation thereof, partly in section.

30 1 designates the piston which is here shown as having a head 2 which is angular or seven sided, the head being formed with a circumferential groove 3 and also with passages leading from the groove 3 out 35 through the piston head and preferably through one of the faces as the rear face of the piston head 2.

As here shown, the piston is formed with a pair of passages located close together 40 which are formed with inwardly or radially extending portions 4 and with portions 5 extending substantially parallel with the axis of the piston and opening through the rear face thereof.

45 6 is a piston ring or cord lying in the groove 3 and having its end portions lapped as at 7 and the parts 8 beyond the lapping portions extending through the passages 4, 5 and being exposed on the rear face of the 50 piston head 2.

When the cord has been drawn taut it may be held from loosening by indenting or upsetting the portion of the metal of the head between the passages 5 as indicated at 9.

55

I have here shown this piston as embodied in a candle molding machine in which 10 designates the mold supported by a suitable frame 11, and the piston 1 is shown as having a hollow stem through which the wick 60 of the candle being molded is drawn.

The mold 10 is open at its top for receiving the melted wax or grease and when the candle is formed and partly cooled it is pushed out of the mold by operating the 65 piston or plunger 1.

Although this piston is shown as adapted for candle molding machines, obviously, it may be useful in other situations such as in 70 grease cups and the like.

70

This construction is particularly advantageous in that it provides an especially simple and economical way of packing the piston.

What I claim is:

75

1. A piston construction comprising a piston head formed with a circumferential groove, and a cord lying in said groove and having its end portions lapped, and the ends thereof brought out of the groove through 80 the piston head, substantially as and for the purpose described.

2. A piston construction comprising a piston head having a circumferential groove and a pair of holes opening into the groove 85 and through the rear face of the piston, and a cord lying in the groove and having its end portions lapped and the parts thereof beyond the lap passed out through said holes, substantially as and for the purpose 90 specified.

3. A piston comprising a head formed with a circumferential groove, and passages extending inwardly or radially from the groove, and a cord lying in the groove and 95 having its end portions lapped and the end portions beyond the lap secured in said passages, substantially as and for the purpose set forth.

4. A piston comprising a piston head hav- 100

ing a circumferential groove, and passages extending radially inwardly from the bottom of the groove, then outwardly through the rear face of the piston, and a cord lying in the groove and having its end portions lapped and the portions thereof beyond the lap drawn into said passage and secured on

the rear face of the piston head, substantially as and for the purpose described.

In testimony whereof, I have hereunto 19 signed my name, at Syracuse, in the county of Onondaga, and State of New York, this 9th day of February, 1917.

EVALD J. ENGMAN.
